UNITED STATES PATENT OFFICE

LOUIS A. M. PHELAN, OF CHICAGO, ILLINOIS, AND PAUL S. BEAR, OF ELKHART, INDIANA, ASSIGNORS, BY MESNE ASSIGNMENTS, TO MINNEAPOLIS-HONEYWELL REGULATOR COMPANY, OF MINNEAPOLIS, MINNESOTA, A CORPORATION OF DELAWARE

ELECTRICAL SWITCH

Application filed October 22, 1927, Serial No. 228,043. Renewed September 8, 1931.

Our invention relates to electrical switches of the liquid flow type and refers particularly to mercury contactors that are adapted for commercial operations and to meet requisite service conditions as to current carrying capacities, voltages, life, reliability, etc.

An object of our present invention is to provide an electrical contactor of the character indicated having an hermetically sealed envelope of glass or other insulating fragile material, electrodes sealed in the envelope and a body of mercury therein and being economical to manufacture and efficient in operation.

Another object of our invention is to provide an electrical contactor having an hermetically sealed container of glass or other fragile material which houses electrodes, a body of mercury and a filling of inert gas, such as hydrogen, the latter being placed within the sealed container after the same has been evacuated of air and other deleterious gases. The container is, of course, hermetically sealed at the points where the leading-in wires for the electrodes extend therethrough and where the container is tipped off through which the air is exhausted and the hydrogen gas or other inert gas is filled into the container. Such seals are sometimes defective but such defects are incapable of being discerned by very careful inspection. By our present invention we apply exteriorly of the container, at the points where the seals are made, a flexible cement which ensures the seals against the development of leaks.

Another object of our invention is to provide a mercury contactor that is completely covered with the aforesaid flexible cement which adheres closely to the exterior walls of the container thereby serving as a protective covering or shock-absorbing medium for the fragile container.

Another object of our invention is to provide a mercury contactor wherein the leading-in wires at the points where they project exteriorly of the envelope and are connected to flexible electrical conductors, the latter serving to connect the contactor to an external electrical circuit, are embedded in a body of cement that holds the flexible conductors in

close contact with the envelope thereby precluding these connections from being broken when the flexible conductors are moved, such as occurs constantly when the electrical contactor is being tilted.

55

Another object of our invention is to provide an electrical contactor mounted in a suitable holder which permits the flexible conductors extending from the contactor to be threaded through the holder thereby minimizing or substantially eliminating all bending action between the flexible conductors and the leading-in wires that are sealed through the glass envelope of the contactor.

60

Another object of our invention is to provide a mercury contactor comprising a tubular container having the leading-in wires sealed at one end thereof and large-headed electrodes at the inner ends of the leading-in wires, the electrodes being so disposed within the container that a minimum diameter of the container is possible while, at the same time, the big-headed electrodes are spaced from each other the proper distance.

65

Another object of our invention is to provide a better understanding of the nature, scope and characteristic features of our invention, reference may be had to the following description and the accompanying drawings, in which—

70

Figure 1 is a top plan view, partially in section, of an electrical contactor embodying one form of our invention;

Fig. 2 is a view, partially in section, and partially in elevation of the contactor illustrated in Fig. 1;

75

Fig. 3 is a top plan view of the device of Figures 1 and 2 showing with particularity a method of embedding the flexible conductors, attached to the leading-in wires, in the flexible cement that serves both to seal the envelope and to protect the connections between the flexible conductors and the leading-in wires from bending movement;

80

Fig. 4 is a plan view of a modified form of a contactor embodying another form of our invention;

85

Fig. 5 is an end view of the contactor of Fig. 4;

Fig. 6 is a side view, partially in section, of another form of our invention;

90

100

Fig. 7 is a plan view of the device of Fig. 6; Fig. 8 is a view in elevation of another form of a contactor embodying our invention; and Fig. 9 is a view in elevation of another modified form of our invention.

Referring to the device shown in Figs. 1, 2 and 3 the contactor comprises an envelope 1 made of fragile material, such as glass, through one end of which leading-in wires 2 and 3 are sealed by employing a pinch seal construction 4 of the character utilized in sealing the leading-in wires in an incandescent lamp bulb. The leading-in wires 2 and 3 are disposed side by side transversely of the tubular container 1. The leading-in wires may be made of any suitable material that is adapted to form permanent hermetical seals with glass such, for instance, as the well known Dumet wire. Of course, these leading-in wires may be made of other materials, that serve to produce more or less satisfactory seals. If the fragile container 1 is made of a high melting glass such as pyrex, the leading-in wires may be made of tungsten. The pinch seal 4 permits the leading-in wires 2 and 3 to extend outwardly beyond the container 1, as shown in the drawings. The leading-in wires 2 and 3 project interiorly of the container 1 and are provided at their inner ends with large-headed electrodes 5 and 6. The container 1 is also evacuated of air and other deleterious gases and preferably filled with an inert gas, such as hydrogen. The exhaustion and the refilling of the container 1 is effected through a tubulation which is shown as being sealed off at 7. A body of mercury 8 is housed within the container 1 and serves to make and break the electrical circuit between the electrodes 5 and 6.

If the leading-in wires 2 and 3 are made of Dumet or other material that is likely to cause deterioration of the contactor in service, the electrodes 5 and 6 are then connected to their respective leading-in wires through rods 9 and 10 made of a suitable material, such as iron or tungsten and which rods, in turn, are welded or otherwise secured at points 11 and 12, respectively, to the leading-in wires 2 and 3. The glass constituting the container 1 is brought down to totally embed the Dumet leading-in wires 2 and 3 thereby precluding their exposure interiorly of the container.

The materials entering the construction of the contactor described may be those set forth in U. S. Patent No. 1,598,874, and the method of attaching the electrodes 5 and 6 to the Dumet leading-in conductors 2 and 3 may be that described in U. S. Patent No. 1,598,875. It is to be understood, of course, that we are not to be limited to the specific materials herein described or thus referred to in the aforesaid patents. The electrodes 5 and 6 may be made of a number of metals, such as

iron, nickel, platinum, cobalt, tungsten, molybdenum as well as alloys, such as nickel-chromium alloys or cobalt-iron alloys. The same materials may be employed for making the rods 9 and 10 that serve to connect the big-headed electrodes 5 and 6 to the leading-in conductors 2 and 3. The container 1 may be made of glass, porcelain, pyrex, quartz or glass known as Q702P and, therefore, when the term "glass" is used herein, it is to be understood that it comprehends within its meaning such materials as are enumerated, as well as other materials that are suitable for making the envelope or container of a mercury contactor.

The pinch seal 4 is of a well known type of construction and has been employed in the manufacture of incandescent lamps when the leading-in wires are sealed into the bulb by a glass sealing machine. Flexible conductors 13 and 14 are connected respectively to the exteriorly projecting portions of the leading-in wires 2 and 3, these flexible conductors preferably constituting a flexible copper conductor having an exterior braided insulating covering. Flexible conductors of this character are well known in the art. The interior conducting elements of the flexible conductors are soldered, welded or otherwise secured, as shown at 15 in Fig. 2, to the leading-in wires 2 and 3. The flexible conductors 13 and 14 are then bent so that the portions thereof adjacent to the points of connection to the leading-in wires are in close contact with the envelope 1. In this manner, the flexible conductors are extended longitudinally of the envelope 1.

The end of the contactor whereat the pinch seal construction 4 obtains is then completely embedded within a flexible cement 16 which closely adheres to the walls of the container and serves as a duplicate seal for the pinch seal construction 4. The cement 16 also impregnates the insulating covering of the flexible conductors 13 and 14 and holds these conductors firmly in contact with the walls of the envelope 1. In this manner the points of connection between the leading-in wires 2 and 3 and the flexible conductors 13 and 14 are wholly embedded within the cement 16 which precludes these points of connection from being subjected to any mechanical strains or stresses that are likely to interrupt the electrical circuit comprising the electrodes 5 and 6. No bending action can be transmitted to these points of connection and, consequently, these connections are retained substantially permanent. The cement 16, besides serving as an extra seal for the pinch seal construction 4 and as a protection for the connections between the flexible conductors 13 and 14 and the leading-in wires, constitutes a shock-absorbing medium for any blows or shocks that otherwise would break the fragile or glass envelope 1. If desired,

the tip 7 of the container 1 may also be embedded in the cement 16 that serves to both augment the seal as well as to protect the tipping-off portion of the container against 5 mechanical injuries.

The cement 16 may be made of various materials but is preferably a flexible cellulose ester cement or heavy pyroxylin cement, such as a solution of celluloid in acetone or alcohol 10 with the addition of a suitable filler. Coloring material may also be added to the cement thereby imparting any desired color to the tip of the envelope, as well as to the pinch seal portion 4. If a green color for the cement 15 16 is desired, Paris green or chromium pigment would be suitable coloring agents for the cement; if a yellow color is desired, lead chromate would be a suitable pigment; if a red color is desired, many of the well known red lake pigments may be employed, and if a white color is desired, zinc oxide, lithopone, or chalk may be employed. Of course, other porcelain cements that adhere 20 to glass and the like may also be suitable. Therefore, the term "cement" as employed herein comprehends within its meaning such materials that are preferably inert and elastic or shock-absorbing when dried, electrically insulating, non-hygrosopic and capable 25 of providing air-tight seals when applied exteriorly of a glass container.

In Figs. 2 and 3 the contactor is shown as being positioned within a clip holder 17, the same being provided at its rear central portion 30 with an opening 18a by means of which the clip holder 17 may be mechanically connected to any suitable operating mechanism. The flexible conductors 13 and 14 are threaded through the clip holder 17 as shown in 40 Fig. 3. The axis of the tilting movement of the contactor coincides with the axis of the opening 18 formed in the clip holder and, therefore, when the flexible conductors 13 and 14 are threaded through the holder 17 45 the mechanical resistance that these conductors may offer to the tilting movement of the contactor is substantially minimized. At the same time, this construction precludes the conductors 13 and 14 from being subjected 50 to bending movements adjacent to the cement covering 16 and the pinch seal 4.

In the specific construction illustrated in Figs. 1 to 5, inclusive, an electrical contactor is shown having a tubular glass container 55 wherein the diameter of the envelope 1 is minimized by reason of my present invention. The electrodes 5 and 6 of the contactor of Figs. 1 to 3, inclusive, possess large heads, are of substantial concentrated mass and are 60 disposed at the same end of the container which embodies the pinch type of seal. As hereinbefore stated, the pinch type of seal is highly advantageous for the reason that contactors embodying this form of seal may be 65 machine made. In this form of contactor the

leading-in wires 2 and 3 extend into the container through the same end, the pinch seal permitting of both leading-in wires to be sealed in the container simultaneously. The leading-in wires 2 and 3 are spaced from each other transversely of the container 1. The big-headed electrodes 5 and 6 are disposed in staggered relation and spaced from each other longitudinally of the container but adjacent to its longitudinal axis. In this manner, the advantages accruing by reason of the big-headed electrodes 5 and 6 may be secured while, at the same time, the diameter of the container 1 is minimized by reason of the staggered positioning of the electrodes 5 and 6 therein. At the same time, a pinch seal may be employed permitting of the contactor to be machine made. The quantity of mercury 8 required in a contactor of this construction is considerably reduced over that which would be required in a contactor wherein big-headed electrodes are placed side-by-side and spaced from each other transversely of the container.

In Figs. 2 and 3, the flexible electrical conductors 13 and 14 are shown as being brought through the body of cement 16 at the top of the envelope 1. In the contactor illustrated in Figs. 5 and 6, the leading-in conductors 13' and 14' are shown embedded in the cement 16 in such manner that they extend longitudinally of the envelope 1 along one of its sides, in this instance, on the side of the container adjacent the rear portion of the clip holder 17. The positioning of the contactor of Fig. 4 within the clip holder 17 is best illustrated in Fig. 5 wherein the flexible conductors 13' and 14' are shown as being superposed upon each other at the end of the envelope but extending longitudinally thereof on that side of the envelope which permits of the flexible conductors 13' and 14' being threaded through the clip holder 17, as shown.

In the contactor of Figs. 6 and 7, the pinch seal construction is used but the electrodes 18 and 19 are shown as constituting extensions to the leading-in wires and as being placed side-by-side and spaced from each other transversely of the container. The electrodes 18 and 19 are not of the big-headed type of construction, such as the electrodes 5 and 6 of the contactor hereinbefore described. If the leading-in wires to which the electrodes 18 and 19 are attached are made 110 of tungsten or some other metal which does not cause deterioration of the contactor and which supply substantially permanent hermetic seal's with the glass container, then no provision need be made for precluding exposure of the leading-in wires interiorly of the container. However, if the leading-in wires to which the electrodes 18 and 19 are attached are made of Dumet, then they should preferably be completely embedded within the glass 120 125

seal so as to preclude their exposure within the container. The electrodes 18 and 19 may be secured to the leading-in wires in any suitable manner, such as by welding or otherwise.

5 The contactor of Figs. 6 and 7 shows the flexible electrical conductors connected to the leading-in wires as being disposed in a manner similar to the leading-in conductors shown in Figs. 4 and 5. The flexible conductors connected to the leading-in wires have their ends adjacent to the points of connection embedded in the body of cement 16. The tip 16' of the container, if desired, may also be embedded in a body of cement, such as I have hereinbefore described. In this fashion, the envelope is provided with a double seal at those points where the glass has been sealed during the manufacture of the contactor.

20 The structure shown in Fig. 8 comprises a contactor similar to that illustrated in Figs. 6 and 7 except that it is of diminutive size. The clip holder in this instance comprises two spaced clip portions 20 and 21 and the
25 rear of the holder is provided with three openings 22, 23 and 24 that serve as mounting means for the contactor.

In Fig. 9 we have shown a mercury contactor of simple construction, the envelope of which is completely covered with the cement that we have described in connection with the pinch seal of the contactors shown in the other figures. The seals are thus provided with a protective coating as well as the whole of the fragile envelope. The cement coating serves as a shock-absorbing medium and permits the contactor to be more roughly handled than has heretofore been possible with contactors not provided with this external flexible cement covering that serves as a shock-absorbing medium.

45 While we have herein described several embodiments of our invention, it is to be understood that many modifications may be made therein without departing from the spirit and scope of the appended claims.

We claim:

1. An electric switch comprising an envelope of fragile insulating material, leading in wires sealed therethrough and terminating at their inner ends in electrodes, a body of mercury in said envelope, and a coating of resilient cement applied exteriorly of said envelope to protect it from mechanical shocks.

2. An electric switch comprising an envelope of fragile insulating material, leading-in wires sealed therethrough and terminating at their inner ends in electrodes, a body 60 of mercury in said envelope, and a substantially impervious and inert coating of resilient and electrical insulating cement adhering to said envelope exteriorly thereof.

3. An electric switch comprising an envelope of fragile insulating material, leading-

in wires sealed therethrough and terminating at their inner ends in electrodes that are disposed adjacent to each other at one end of said envelope, a body of mercury in said envelope, an inert gas filling for said envelope, and a substantially air-tight protective coating of resilient and inert cement applied exteriorly of said envelope and super-sealing said envelope whereat it has been hermetically sealed through the application of heat said resilient cement serving to protect said envelope from mechanical shocks. 70 75

4. An electric switch comprising a container of fragile insulating material, leading in wires sealed therethrough and terminating at their inner ends in electrodes, a body of mercury in said container, and an air-tight coating of electrical insulating and resilient cement enveloping completely said container, said coating serving as a cushion for the walls of said container. 80 85

5. An electric switch comprising an envelope of fragile insulating material, leading-in wires sealed therethrough at one end of said envelope and terminating at their inner ends in electrodes that are positioned adjacent to where said leading-in wires are sealed through said envelope, a body of mercury in said envelope, and an air-tight protective coating of resilient and insulating cement applied exteriorly of said envelope adjacent to those points whereto said leading-in wires are sealed therein to protect said envelope from mechanical shocks. 90 95

6. An electric switch comprising an envelope of fragile insulating material, leading-in wires sealed therethrough at one end of said envelope and terminating at their inner ends in electrodes that are positioned at one end of said envelope, a body of mercury in said envelope, flexible conductors connected to said leading-in wires, and a resilient protective coating of cement applied exteriorly upon said envelope adjacent to the points whereat the said leading-in wires are sealed therein, said cement embedding the points of connection of said flexible conductors to said leading-in wires and serving to protect said envelope from mechanical shocks. 100 105 110

7. An electric switch comprising an elongated envelop of fragile insulating material, leading-in wires sealed there-through at one end of said envelope and terminating at their inner ends in electrodes that are positioned at one end of said envelope, a body of mercury in said envelope, flexible conductors having an insulating covering and being connected to said leading-in wires, and a body of resilient cement applied exteriorly of said envelope and impregnating the insulating covering of the flexible conductors whereby the portions thereof adjacent to the points of connection to said leading-in wires are held firmly in close contact with the wall of said envelope.

envelope, said resilient cement serving to protect said envelope from mechanical shocks.

8. An electric switch comprising an elongated envelop of fragile insulating material, leading-in wires sealed there-through one end thereof and terminating at their inner ends in electrodes positioned at one end of said envelope, a body of mercury in said envelope, 10 flexible conductors having an insulating covering and being connected to said leading-in wires, and a body of insulating and resilient cement applied exteriorly of said envelope adjacent to the seals of the leading-in wires, embedding therein the points of connection 15 between said leading-in wires and said flexible conductors and holding said flexible conductors in close contact with said envelope said resilient cement serving to protect said 20 envelope from mechanical shocks.

9. An electric switch comprising an envelope of glass having leading-in wires sealed therein adjacent to one end of said envelope and terminating at their inner ends in electrodes, a body of mercury in said envelope, the latter being tipped off, and a coating of 25 resilient air-tight cement applied exteriorly of said envelope, and embedding the tipped-off portion thereof and the seals through 30 which the leading-in wires are admitted within said envelope.

10. An electric switch comprising a tubular elongated container, leading-in wires sealed in said container through the medium 35 of a pinch seal and spaced from each other transversely of said tubular container, large headed electrodes interiorly of said container connected to said leading-in wires and spaced from each other longitudinally of the 40 container, and a body of mercury in said container.

11. An electric switch comprising an elongated glass container, spaced leading-in wires sealed at one end of said container 45 through the medium of a pinch seal, said leading-in wires being spaced from each other transversely of the container, electrodes disposed within said container and connected to said leading-in wires, said electrodes constituting enlarged heads that are spaced from 50 each other along the longitudinal axis of said container, a body of mercury housed in said container, flexible conductors connected to said leading-in wires exteriorly of said container, and a body of insulating cement embedding the exterior portions of said leading-in wires and holding said 55 flexible conductors in close contact with the exterior surface of said container.

12. An electric switch comprising an elongated glass container, spaced leading-in wires sealed at one end thereof through the medium of a pinch seal whereby said leading-in wires are spaced from each other transversely of the container, electrodes disposed

within said container and connected to said leading-in wires, said electrodes constituting enlarged heads that are spaced from each other along the longitudinal axis of said container, a body of mercury housed in said 70 container, flexible conductors connected to said leading-in wires exteriorly of said container, a body of electrical insulating and hermetically sealing cement embedding the exterior portions of said leading-in wires and holding said flexible conductors in close contact with the exterior surface of said container, and a filling of hydrogen gas within 75 said container.

13. An electric switch comprising an elongated glass container of insulating material, leading-in wires sealed at one end thereof through the medium of a pinch seal, enlarged electrodes within said container and disposed at one end thereof, said electrodes being spaced from each other along the longitudinal axis of said container which is tipped off at its end opposite to said pinch seal, a body of mercury in said container, flexible 80 conductors connected to said leading-in wires exteriorly of said container, an insulating cement embedding the pinch seal and the points of connection between said flexible conductors and said leading-in wires, and a second body of cement embedding the tipped-off portion of said container. 85

14. An electric switch comprising an elongated tubular container of fragile insulating material, leading-in wires sealed at one end thereof through the medium of a pinch seal, enlarged headed electrodes on the inner ends of said leading-in wires and positioned in the end of the container adjacent the pinch seal, flexible conductors connected to the exterior portions of said leading-in wires, a body of mercury in said container and a body of insulating and resilient cement embedding the pinch seal and the points of connection between said leading-in wires and said flexible conductors whereby said flexible 100 conductors are held adjacent to the pinch seal, said cement protecting said envelope from mechanical shocks. 105

15. The combination with a holder, of an electric switch disposed therein and held by said holder about its central portion, said electric switch comprising a tubular container, leading-in wires sealed at one end thereof, electrodes disposed in said container and connected to said leading-in wires, a body of mercury in said container, flexible conductors connected to said leading-in wires exteriorly of said container, and a body of insulating and insulating cement embedding the exterior portions of said leading-in wires at the points of connection between the said flexible conductors and said leading-in wires and holding said flexible conductors in close contact with said container thereby permitting the said flexible conductors to be extended longitudi- 115 120 125 130

nally of said container and through said holder.

16. An electric switch comprising a tubular elongated container, leading-in wires sealed in said container through one end thereof and spaced from each other transversely of said container, enlarged headed electrodes in said container that are connected to said leading-in wires and spaced from each other a relatively short distance longitudinally of the container, and disposed at one end of said container, and a body of mercury in said container.

17. An electric switch comprising a tubular elongated container, leading-in wires sealed therein and spaced from each other transversely of said container, enlarged headed electrodes housed in said container and at one end thereof that are severally connected to said leading-in wires and spaced a relatively short distance from each other longitudinally of the container, and a body of mercury in said container.

18. An electric switch comprising an hermetically sealed container of fragile insulating material, a leading-in wire sealed therethrough and terminating at its inner end in an electrode, a body of mercury in said container and an air-tight coating of cement applied exteriorly to said container and covering at least that portion thereof whereat said leading-in wire is sealed through said container, said cement providing an additional hermetic seal around said leading-in wire seal and protecting said container thereat from mechanical shocks.

In witness whereof, we have hereunto subscribed our names.
